UNITED STATES PATENT OFFICE.

WILLARD ALLEN SPEAKMAN, OF WILMINGTON, DELAWARE, ASSIGNOR TO SPEAKMAN COMPANY, OF WILMINGTON, DELAWARE, A CORPORATION OF DELAWARE.

WASTE AND OVERFLOW CONNECTION.

Application filed August 7, 1926. Serial No. 127,847.

The general object of the present invention is to provide an improved waste and overflow connection for a bath tub or other lavatory receptacle, which is so mounted as to render the overflow and waste piping inaccessible. More specifically, the object of my present invention is to provide a bath tub or other receptacle with a waste and overflow connection having desirable sanitary characteristics and comprising a waste valve and operating mechanism for the latter which passes through the overflow connection, is simple in construction, effective in operation, and comprises provisions for readily effecting such adjustments as may be required, notwithstanding the fact that the waste and overflow piping is so located as to be permanently inaccessible.

5 to 10 15 20 25 30 35 40 45 50 55 60 65 70 75 80 85 90 95 100 105 110

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described preferred embodiments of my invention.

30 Of the drawings:

Fig. 1 is a vertical section of the fixture applied to a built-in bath tub;

Fig. 2 is a front view of the overflow strainer;

35 Fig. 3 is a plan view of the outlet strainer; and

Fig. 4 is a vertical section of a modification of the adjusting means.

In the drawings A represents a so-called 40 built-in bathtub set against the bathroom wall B so as to permanently enclose the bath overflow and waste piping. Located in the bottom of the tub A, and adjacent the end wall A' of the latter is a waste outlet opening A². Located in and near the top of the end wall A' is an overflow outlet opening A³. A vertical overflow pipe C' is arranged between the tub end wall A' and the room wall B and is secured at its upper end to an elbow C², and at its lower end to a T C³. The elbow C² is connected by a threaded connection to a sleeve C⁴ secured in the overflow opening A². A horizontal waste pipe C⁵ located below the floor line is connected at one 45 50 55 60 65 70 75 80 85 90 95 100 105 110 end to the T C³, and at the other end to an

elbow C⁶, in threaded engagement with a sleeve C⁷, passing through the waste outlet opening A². An outlet pipe C⁸ for the waste and overflow is slipped into the lower end of the vertical T C³. The pipe joints are provided wherever necessary with suitable packing provisions shown as of usual form.

The sleeve C⁷ in the waste opening A² is provided with a tapered seat C⁹ for a waste valve D of the pop-up type. The valve D consists of a tapered head D' arranged to be seated in the valve seat C⁹. Secured to the underside of the valve head D' is a neck portion D², carrying at its lower end suitably spaced radial guide ribs D³. The guide ribs D³ contact with the cylindrical walls of the sleeve C⁷ and are connected at the base by an annular ring D⁴ adapted for engagement by a subjacent portion of the valve operating mechanism when the valve is to be raised into its open position.

The waste valve operating mechanism comprises an L-shaped rod located in the L-shaped portion of the waste and overflow piping formed by the pipes C' and C⁵, T C³, and elbow C⁶. The vertical and horizontal arms E' and E² of the L-shaped rod are connected by an integral rounded heel portion E³ which projects to the rear of the vertical arm E' and forms a guide bearing against the rear vertical wall of the T C³ and serving to hold the vertical arm E' in a more or less central position in the pipe C'. The arm E² passes beneath the ring portion D⁴ of the valve D, and has its free end received in and guided by the vertical walls of a narrow vertically disposed recess C¹⁰ formed in the elbow C⁶ at the opposite side of the valve D from the T C³.

The upper end of the arm E' is connected to a vertically movable handle located in front of the end wall A' of the bath tub having a knob E⁴ at its top and a lower tubular body portion E⁵. The connection between the handle and arm E', in the construction shown in Figs. 1, 2, and 3, comprises a bent rod E⁶ having a body portion extending through and substantially parallel to the axis of the sleeve C⁴. The rod E⁶ has a depending lower end portion detachably connected to the upper end of the rod E' by a threaded sleeve E⁷ into which the adjacent oppositely threaded end portions of the arm E' and member E⁵ are screwed. The up-

wardly extending front end portion of the rod E⁵ is screwed into an internally threaded bushing E⁷ which is received into the tubular handle portion E⁸. Bolts E⁹, threaded through the wall of the body portion E⁸, have their inner ends projecting into a circumferential groove formed in the part E⁷ thereby permitting the handle to be rotated relative to the bushing E⁷, while preventing relative movements of the knob and bushing in the direction of their common axis. A set screw E¹¹ is provided, as shown, for normally holding the bushing E⁷ against rotative movement relative to the member E⁸.

The body portion E⁸ of the handle is movably received in a tubular guide portion F⁵ of a member F detachably secured to the bathtub as by means of screws F³ tapped into the out-turned front flange of the sleeve C⁴. Preferably, and as shown, the part F comprises an apertured portion F' forming a strainer in front of the passage through the sleeve C⁴. As shown, vertical slots F⁴ are formed in the wall of the cylindrical passage formed in the member F for the body portion E⁸. The slots F⁴ receive the heads of the bolts E⁹ when the valve D is closed, but when the knob E⁴ is lifted to move the valve D into its fully open position, the heads of the bolts are lifted above the part F and the knob may then be rotated to swing the bolt heads out of register with the slots F⁴, so that the heads of the bolts E⁹ may then rest on the top of the guide F and thereby hold the valve D in its wide open position.

A strainer F² is provided for the waste outlet opening A². As shown, the strainer F² comprises finger-like portions, the lower ends of which are out-turned and may be sprung into a groove C¹⁰ formed in the upper end of the sleeve member C⁷, to thereby detachably secure the strainer F² in place.

The closed position of the valve D, and the corresponding position of its operating mechanism are shown by the full lines in Fig. 1. When it is desired to open the valve, the knob E⁴ is raised to the position shown by the dotted lines in Fig. 1 where the bolt heads E⁹ are above the slots F⁴. The knob is turned to allow the bolt heads to rest on the handle guide F⁵. The vertical movement of the knob raises the valve operating rod and through the arm E² of the latter lifts the valve D into its open position allowing the fluid contents of the tub A to flow through the valve opening and the pipe C⁵ to the outlet pipe C⁸. The end of the arm E² is guided in its vertical movement by the side walls C¹⁰ of the elbow C⁶, and the heel E³ moving in contact with the vertical rear wall of the T C³ maintains the position of the arm E² centrally of the pipe C'. When it is desired to close the valve D, the knob E⁴ is turned until the bolt heads E⁹ engage

in the vertical slots and the operating mechanism is pushed down or drops by gravity to its normal position. The valve D returns to its normal closed position by gravity.

In a preferred mode of assembling the apparatus, the rod E', E² is passed through the T C³, and the pipes C' and C⁵ are then secured to the T C³. The rod E⁵ is then coupled by the sleeve E⁶ to the upper end of the arm E'. After this the elbows C² and C⁶, secured to the pipes C' and C⁵, are anchored against the tub A by screwing the sleeves C⁴ and C⁷, respectively, into place. The part F is next slipped over the threaded end of E⁵ and dropped down until the bottom of the guide portion F⁵ of the member F rests on the horizontal portion of the part E⁵. The bushing E⁷ is then screwed onto the upper end of the part E⁵ to the proper distance which is that which insures the wide open position of the valve D when the heads of the bolts E⁹ are resting on the upper end of the guide part F⁵, and which will insure a slight clearance between the valve ring portion D⁴ and the arm E² in the valve closed position of the parts.

After the effective length of the valve operating member is thus adjusted, the set screw E¹¹ is tightened to prevent the parts from working out of adjustment. Ordinarily the length of the valve operating member will be initially adjusted or readjusted if necessary with the bolts E⁹ loosened so that the handle is disconnected from the bushing E⁷.

The waste and overflow piping required with the present invention may be of standard construction, except for the guide slot C¹⁰ in the elbow C⁶. The waste valve and its operating mechanism are obviously simple in construction and reliable in operation, and the inaccessible portion of the valve operating member is of such a character and so disposed that there is practically no possibility of its breaking or becoming inoperative. In particular it can readily be made so strong as to avoid all reasonable possibility of its being strained beyond its elastic limit and thereby deformed, as result of a pull on the handle knob E⁴, even though that pull be very greatly in excess of the maximum required. The tendency of an excessively strong pull on the handle to permanently bend the rod E', E² is minimized by the fact that in such case the arms E' and E² form a sort of a lever for which the back wall of the T C³, engaged by the heel portion E³, serves as a fulcrum, so that the lateral elasticity of both arms E' and E² may be utilized in absorbing the excessive pull on the handle knob.

The overflow and waste connection as a whole is of a highly desirable form from the sanitary standpoint. The location of the waste valve permits it to be readily cleaned

with or without its entire removal, and also prevents any contamination of the water in the tub by foul water or dirt in the pipe C⁵, under ordinary conditions of use, such as 5 may occur with a waste valve engaging a seat in the outlet piping at some distance from the waste outlet opening of the tub. The form and disposition of the waste valve operating member are such as to minimize 10 the tendency of waste solids to accumulate in the waste or overflow piping. A desirable characteristic of the valve operating mechanism is the location of the handle knob E⁴ above the overflow outlet A³, and 15 thereby above the maximum water level in the tub, so that the handle knob is visible at all times, and cannot become fouled by scum floating on the water in the bathtub. The presence of such scum on the valve operating 20 handle knob would interfere with the operation of the valve and be otherwise objectionable.

In Fig. 4 is shown a modified form of an adjustable connection between the rod E' and handle knob E⁴. The connection shown 25 in Fig. 4 comprises an L-shaped part E⁵⁰ having a depending leg with a threaded socket into which the upper end of the arm E' is screwed. The free end of the other 30 leg of the part E⁵⁰ has journaled in it a nut H' through which a vertically adjustable bolt H² is threaded. The bolt H² at 35 its upper end is screw threaded into the body part E⁸⁰ of the handle, and is held in position therein by a set screw E¹¹. The 40 adjustments of the valve operating means shown in Fig. 4 are obtained by moving the nut H' up or down on the bolt H². H³ is a lock nut for securing the parts in any desired adjustment.

While in accordance with the provisions of the statutes, I have illustrated and described the best form of embodiment of my invention now known to me, it will be apparent 45 to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I desire to secure by Letters Patent, is: 55

1. The combination with a lavatory receptacle having a bottom waste outlet and a lateral overflow outlet, of a waste and overflow connection comprising a vertical pipe with a lateral connection at its upper end to said 60 overflow outlet and a horizontal pipe connected to said waste outlet and to said vertical pipe, a valve controlling flow through said waste outlet, a rigid operating member extending through said overflow outlet into said pipes and adapted to operate said

valve when raised and lowered, and having a vertical portion at its upper end, and a stationary guide for said vertical portion.

2. The combination with a lavatory receptacle having a bottom waste outlet and a lateral overflow outlet, of a waste and overflow connection comprising a vertical pipe with a lateral connection at its upper end to said overflow outlet and a horizontal pipe connected to said waste outlet and to said vertical pipe, a valve controlling flow through said waste outlet, a rigid operating member extending through said overflow outlet into said pipes and adapted to operate said valve when raised and lowered, a handle 75 and an adjustable connection between said handle and the upper end of said member accessible for adjustment at the inner side of said receptacle.

3. The combination with a lavatory receptacle having a bottom waste outlet and a lateral overflow outlet, of a waste and overflow connection comprising a vertical pipe with a lateral connection at its upper end to said overflow outlet and a horizontal pipe 80 connected to said waste outlet and to said vertical pipe, a valve controlling flow through said waste outlet, a rigid operating member extending through said overflow outlet into said pipes and adapted to operate 85 said valve when raised and lowered, said member having a vertical portion at its upper end, a guide member having a vertical groove and secured to said receptacle, a handle 90 vertically movable in said guide member and having a lug arranged to move in the vertical groove of said member, and a swivel connection with the vertical portion of said operating member and said handle.

4. The combination with a lavatory receptacle having a bottom waste outlet and a lateral overflow outlet, of a waste and overflow connection comprising a vertical pipe connected at its upper end to said overflow outlet and a horizontal pipe connected to 95 said waste outlet and to said vertical pipe, a valve controlling flow through said waste outlet, a rigid valve operating member having a vertical portion in said vertical pipe and a lower horizontal portion in said horizontal pipe adapted to operate said valve 100 when raised and lowered, and vertical guide surfaces for the free end of the horizontal portion of said operating member.

5. The combination with a lavatory receptacle having a bottom waste outlet and an upper overflow outlet, of a waste and overflow connection comprising a vertical pipe with a connection at its upper end to said overflow outlet, a T connected to the 110 lower end of said vertical pipe and a horizontal piping connected to said waste outlet and to said T, a valve controlling the flow through said waste outlet, and a rigid valve 115 operating member comprising a vertical por-

- tion in said vertical pipe, a horizontal portion in said horizontal piping and a rounded heel portion connecting said vertical and horizontal portions and adapted to slide 5 along and be guided by the vertical wall of said T remote from said waste outlet, and vertical guiding means in said horizontal piping for the free end of the horizontal portion of said member.
- 10 6. The combination with a lavatory receptacle having a bottom waste outlet and an upper overflow outlet, of a waste and overflow connection comprising a vertical pipe connected at its upper end to said overflow outlet, a horizontal pipe connected at one 15 end to the lower end of said vertical pipe, an

elbow fitting connecting the other end of the horizontal pipe to the waste outlet, a valve controlling the flow through said waste outlet, and a rigid valve operating member comprising a vertical portion in said vertical pipe and a horizontal portion in said horizontal pipe, said elbow fitting being formed with a narrow vertical guideway receiving the free end of the horizontal portion of said member, and located at the opposite side of said waste valve outlet from said vertical pipe.

Signed at Wilmington, in the county of New Castle, and State of Delaware, this 4th day of August, A. D. 1926.

WILLARD ALLEN SPEAKMAN.
